UNITED STATES PATENT OFFICE.

JOSEPH PAGANO, OF MEMPHIS, TENNESSEE.

GASOLENE CUT-OFF.

1,148,932.

Specification of Letters Patent.

Patented Aug. 3, 1915.

Application filed August 28, 1914. Serial No. 859,032.

To all whom it may concern:

Be it known that I, JOSEPH PAGANO, a citizen of the United States, and a resident of Memphis, in the county of Shelby and State of Tennessee, have made certain new and useful Improvements in Gasolene Cut-Offs, of which the following is a specification.

My invention is an improvement in gasolene cut offs, and has for its object to provide a device of the character specified, for use in connection with liquid fuel engines, wherein mechanism is provided for automatically cutting off the liquid fuel at the supply tank from the carburetor, when the engine stops running and wherein other mechanism is provided in connection with the intake of the manifold and operated by the suction generated in the cylinder of the engine by the piston for connecting the supply tank with the carburetor.

In the drawings is shown a diagrammatic view of the improved cut off in use, showing its arrangement and connections.

The present embodiment of the invention is shown in connection with the carburetor 1 of an engine, the carburetor being connected with the intake manifold 2 of the engine. The fuel tank 3 is of ordinary construction, having the filling opening closed by a plug 4, and having a discharge pipe 5 near its bottom. A valve casing 6 connects the discharge pipe 5 with the tube 7 which leads to the carburetor, and opens in the fuel chamber thereof.

The valve casing 6 it will be noticed is provided with transverse passages offset laterally with respect to each other, each passage being in a laterally extending nipple 8 and 8^a respectively. The passages are connected by the bore 9 of the valve casing, and it will be noted that each of the pipes 5 and 7 is connected to the adjacent nipple 8 and 8^a by means of unions 10 to form fluid tight joints. A needle valve 11 co-operates with the valve casing 6, being arranged in the bore 9, and a packing 12 is arranged around the needle valve, to make a fluid tight joint at the outer end of the same.

An externally threaded ring 13 is connected with the valve casing 6, by means of arms 14, and a cylinder 15 is engaged with the ring. The open end of the cylinder is internally threaded, as shown, and engaged with the threads of the ring, and at the opposite end from the casing the cylinder

has a central internally threaded port or passage 16.

A piston 17 is arranged within the cylinder, said piston having an internally threaded socket 18 at its center, and the outer end of the needle valve 11 is threaded to engage the socket. A lock nut 19 is provided for preventing disengagement of the needle valve. A plug 20 closes the outer end of the port or passage 16, the plug being threaded into the port or passage, and the said plug has an axial opening.

A coil spring 21 is arranged between the plug and the piston, and normally acts to press the piston toward the valve casing 6, and in a direction to cause the needle valve 11 to cut off all communication between the passages 8 and 8^a. A tube or pipe 22 connects the plug 20 with a laterally extending nipple 23 on the intake manifold between the carburetor and the connection of the manifold with the engine. Unions 24 and 25 are used for connecting the pipe or tube 22 with the plug 20 and with the nipple 23 respectively.

The operation of the device is as follows: The spring 21 normally holds the needle valve 11 closed, to cut off communication between the passages 8 and 8^a, that is between the fuel tank and the carburetor. When the pistons of the cylinders of the engine move outward on the suction stroke, a partial vacuum is created in the cylinder 15 between the piston 17 and the closed end of the cylinder. The pressure of the air on the opposite face of the piston overcomes the resistance of the spring 21, and moves the piston toward the plug 20, thus causing the needle valve to place the ports 8 and 8^a in communication with each other to a greater or less degree, depending upon the force of the suction.

When the engine is not running the spring 21 will through its action on the piston and the needle valve positively cut off the fuel tank from the carburetor, so that no fuel is fed except when the engine is running. It is not necessary for the operator to close any valves between the tank and the engine to prevent flooding of the carburetor or waste of fuel, since this closing or cut off is absolutely automatic in its action.

By means of the valve stem 11 and the lock nut 19 the tension of the spring 21 may be varied. It is obvious that when the piston is moved toward the valve casing 6 the

spring 21 will be weaker than when the piston is moved toward the plug. By turning the valve stem of the socket 18 the distance between the piston and the plug 20 may be varied.

I claim:

1. A device of the character specified, comprising in combination with the carbureter, the manifold intake, the fuel tank, and the connection between the fuel tank and the carbureter, of a valve casing interposed in the said connection, said casing having passages out of alignment with each other and connected by the bore of the casing, said passages being connected with the fuel tank and the carbureter respectively, a valve in the casing, a cylinder supported by the casing co-axial with the bore of the casing, a piston in the cylinder connected with the valve, a spring arranged between the piston and the cylinder and normally holding the valve closed, and a connection between the end of the cylinder remote from the valve casing and the manifold intake.
2. A device of the character specified, comprising in combination with the carbureter, the manifold intake to which the carbureter is connected, the fuel supply tank, and the connection between the supply tank and the carbureter, of a valve casing interposed in the said connection and having passages offset laterally with respect to each other for connecting the fuel tank to the carbureter, said passages being connected by the bore of the valve casing, a valve in the casing, a cylinder supported by the casing, a piston in the cylinder adjustably connected to the valve, a spring normally press-

ing the cylinder in a direction to close the valve, and a connection between the cylinder and the manifold intake between the carbureter and the piston.

3. A device of the character specified, comprising in combination with the carbureter, the manifold intake to which the carbureter is connected, the fuel supply tank, and the connection between the supply tank and the carbureter, of a valve interposed in the said connection, a cylinder arranged adjacent to the valve, a piston in the cylinder, a connection between the piston and the valve for operating the same when the piston is moved, a spring normally holding the valve closed, a connection between the cylinder and the manifold intake between the carbureter and the engine, and means for varying the tension of the spring.

4. A device of the character specified, comprising in combination with the carbureter, the manifold in-take to which the carbureter is connected, the fuel supply tank and the connection between the supply tank and the carbureter, of a valve interposed in the said connection, a cylinder at the valve and connected with the manifold in-take, a piston in the cylinder, a spring normally acting to move the piston in the opposite direction to that which it would be moved by a decrease of air pressure in the manifold in-take, and an adjustable connection between the piston and the valve for operating the valve when the piston is moved.

JOSEPH PAGANO.
